ABSTRACT: An apparatus for mining ore of a type which is located in relatively narrow strata within the earth whereby it is profitably disadvantageous to move large quantities of earth so to gain physical access thereto, the apparatus comprising means for sawing away of the narrow strata by a flat elongated endless chain saw mechanism mounted on a pair of carriages riding on rails in parallel tunnels, the mechanism having a thickness of approximately the thickness of the ore-bearing strata and the chain saw extending transversely between the tunnels wherein the ground material is sluiced into the tunnels and a pumping station provided to transport the material to the surface.

MINING METHOD AND APPARATUS THEREFOR

This invention relates generally to mining machinery. More specifically it relates to a method and machinery for the mining of ores of valuable minerals such as gold and the like, and wherein the precious metal or mineral is most concentrated in a relatively thin strata of the earth and which may extend rectilinearly over a long plane of distance.

Priority is claimed under Pat. application No. 65/3788 in the Republic of South Africa and accepted for examination by the Registrar of Patents on Oct. 15, 1967.

Heretofore the conventional mining of such mineral deposits required the construction of tunnels, and galleries with branching passageways and drifts at different levels, and thereafter drilling, blasting, pneumatic hammering and digging to remove the mineral-bearing ore out of the mine. It is of course understood that such passageways and the excavations therebetween follow the vein or strata of precious mineral bearing ore, and that in order to gain physical access thereto the excavations must be sufficiently high so to permit entrance of men and machinery, which thereby requires the movement of great quantities of rubble and nonore-bearing earth so to mine out the strata. Many valuable minerals such as gold are concentrated as a rule in narrow zones of the order of one or two inches in thickness, thereby making unprofitable the movement of several feet in height of earth.

Additionally in conventional mining a working face transverse to the direction of the passages may be dug out by following the strata. This is known as stoping. It makes possible the recovery of the entire ore strata between two levels of passages. The stope, i.e. the worked-out part of the mine behind the working face, is again filled up with rubble and nonpaying earth, or simply allowed to collapse as the working face advances. In some situations it may be necessary to leave unmined columns or pillars standing so as to support the weight of the earth above and prevent collapse or squeezing down of the earth for purposes of safety to the miners underground, such remaining pillars containing the ore-bearing strata which cannot be taken. It is of course regrettable to leave such ore-bearing columns, and accordingly attempt may be made to leave a minimum of such columns which of course is attendant with danger. Additionally the presence of men at the working face is always a source of danger and a place of many mining accidents. Thus it is evident that conventional underground mining of precious mineral-bearing ore has numerous and serious limitations.

Accordingly it is a principal object of the present invention to provide a new method for the mining of precious mineral-bearing strata which may be conducted from an area remote from the working face of the ore deposit forming the strata, thereby decreasing the liability of accidents to the miners.

Yet another object of the present invention is to provide a new method for the mining relatively narrow strata of ore which eliminates the necessity of moving great masses of earth adjacent thereto so as to gain physical access to the strata.

Yet a further object is to provide a new method for the mining of narrow strata of ore which in view of the above feature will decrease mining costs and thus permit the profitable mining of lower concentrates of ore which heretofore could not be profitably mined.

Yet a further object of the present invention is to provide a mining machinery for mining according to the above-described method and which includes a relatively thin chain saw mechanism for entering the thin layer of ore-bearing strata and sawing out the ore, the mechanism being operated from a convenient tunnel alongside the strata.

Other objects are to provide a mining method and apparatus therefor which is simple in design, inexpensive to manufacture, rugged in construction, easy to use and efficient in operation.

These and other objects will be readily evident upon a study of the following specification and the accompanying drawing wherein:

FIG. 1 is a perspective view of the present invention shown in operation.

FIG. 2 is an elevational longitudinal section view of a mine incorporating the present invention in its operation.

FIG. 3 is a cross-sectional view in elevation of a section of earth including an ore-bearing strata.

FIG. 4 is a view similar to FIG. 3 showing the present invention applied thereto for mining out the ore-bearing strata.

FIG. 5 is a section along a strike taken on line 5-5 of FIG. 3 and showing initially bored openings for receiving a toothed chain of the present invention.

FIG. 6 is a fragmentary detail of the toothed chain.

FIG. 7 is a longitudinal section view taken on line 7-7 of FIG. 4.

FIG. 8 is a fragmentary detail of a cutting cylinder.

Referring now to the drawing in detail, the reference numeral 10 represents a mining apparatus according to the present invention wherein there is a chain cutter 11 that is supported at its opposite ends on mine cars 12 and 13 located in different tunnels or passageways 14 and 15 of a mine 16.

According to the invention, the chain cutter 11 includes a pair of chain-driving gears 17 and 18 between which an endless heavy duty chain 19 is carried. The chain is provided with a plurality of diamond-encrusted links 20 which additionally may incorporate tungsten carbide slugs. The links 20 may be flat cylindrical or of other shape.

A drive mechanism 21 is mounted on each of the cars for selective use, the drive mechanisms including appropriate structure for supporting the gears, and the drive mechanisms being powered by conventional electrical motors with associate controls.

In the ground, the ore-bearing strata may be found to be located in any of various planes due to the geological upheavals and other natural forces that over the ages twist the earth's crust. Accordingly the strata in the mine may be on a horizontal plane, a vertical plane or on inclined planes which are inclined at all various angles between a horizontal and vertical plane. The strata of a gold-bearing ore generally will be found to be of from one to two inches in thickness. In mining out such a stratum a chain cutter will be used which is comfortably in excess of this dimension so as to positively include the entire thickness of the strata therewithin.

In operative use, a plurality of openings 22 are initially bored along the strata 23 between the tunnels or passageways 14 and 15, as shown in FIG. 5. The openings 22 are enjoined

45 to form a sufficiently large enough space for insertion of the chain 19 therethrough. A similar like-bored opening allows return of the chain, the ends of which are then enjoined, the chain being mounted on the gears 17 and 18. The drive mechanism is turned on so that the cutter chain travels through the bored openings in the ore-bearing strata and around the gears. Meanwhile the mine cars 12 and 13 are simultaneously advanced to slowly travel along the rails 24 into a forwardly direction as indicated by arrow 25. The forward portion of the chain with its links 20 thus engages the working face 26 of the ore-bearing strata which it now

55 proceeds to grind away. Various methods may be employed for gathering the ground-off ore, such methods comprising means to move the ore toward one of the tunnels. The thickness of the section sliced out by the cutter chain will depend upon the thickness of the zone of concentrated mineralization. In a preferred method the rock material of the slice is comminuted simultaneously with its being cut out of the rock.

60 The comminuted rock material may be removed from the vicinity of the line of cutting in the form of dust, chips, and/or sludge by mechanical, pneumatic or hydraulic means, or by a combination of any of these. For example, dust and rock chips may be blown to the surface through piping by means of compressed air similarly as dry cement is blown over long distances. The sludge may be collected in sludge sumps and pumped to the surface by sludge pumps such as by the three

65 row ram pumps 27.

These ores may then be pulverized and subjected to specific treatments for separation of the valuable minerals from the residue rock.

In FIG. 2, the mine 16 is shown to incorporate a pump column 28 between a pump chamber 29 and a metallurgical plant 30. Pulp stream or slurry 31 flows to the pump chamber 29.

In FIG. 8 a cutting cylinder 32 is shown as a means for grinding away the working face of the strata, instead of employment of the cutter chain. In the present construction, the cutting cylinder would be rotatable about its central axis, such motion being provided from appropriate driving mechanisms at its opposite ends carried upon the mine carts.

As the mining operation progresses, the space 33 behind the chain cutter 11 or cutting cylinder 32 is ignored so that it may squeeze together by earth pressure from above, such space comprising a seam of so narrow in thickness that it will cause no problems for overhead support after being squeezed together.

Thus there has been provided a new method and apparatus for mining of relatively narrow strata of valuable minerals which promotes safety, increases mining profit and permits operation of lower grade ore.

While various changes may be made in the detail construction, it is understood that such changes will be within the spirit

and scope of the present invention as is defined by the appended claims.

I claim as follows:

1. Apparatus for mining a relatively narrow ore stratum, comprising parallel tunnels with carriage rails, a pair of similar carriages with wheels mounted on said rails, chain-driving gears mounted on said carriages in combination with an endless chain mounted on said gears extending generally in straight lines parallel to the stratum and transversely to the axis of the tunnels, each gear being operated by a drive mechanism on said carriages, continuously in the same linear direction, ore-cutting means mounted on the chain, wherein said ore-cutting means being substantially the same thickness as said ore stratum.
2. An apparatus as in claim 1 wherein the cutting means comprise diamond-encrusted links encompassing the chain, and wherein the angle between the chain and vertical direction varies of 0° to 90°.
3. An apparatus as in claim 1 further including means for pumping the ground material from the stratum to the tunnels and a surface metallurgical plant.
